UNITED STATES PATENT OFFICE.

ORLA C. PIXLEY, OF CHICAGO, ILLINOIS.

CUTTING AND DELIVERY TABLE FOR TILE-FORMING MACHINES.

SPECIFICATION forming part of Letters Patent No. 734,942, dated July 28, 1903.

Application filed December 20, 1902, Serial No. 136,063. (No model.)

To all whom it may concern:

Be it known that I, ORLA C. PIXLEY, a citizen of the United States, residing at Chicago, in the county of Cook and State of Illinois, have invented certain new and useful Improvements in Cutting and Delivery Tables for Tile-Forming Machines, of which the following is a specification.

The object of this invention is the production of an improved apparatus for receiving the continuous stream of plastic tile from a tile-forming machine, for cutting said continuous tile into suitable lengths, and for delivering the short lengths so formed onto pallets for removal to the dry-room.

In the accompanying drawings, Figure 1 is a top plan view of an apparatus embodying the features of my invention. Fig. 2 is a longitudinal vertical section on dotted line 2 2 of Fig. 1, save that the tile is shown in elevation. Fig. 3 is a rear end elevation of the apparatus. Fig. 4 is a transverse vertical section on dotted line 4 4 of Fig. 1.

In the embodiment herein shown of this invention I provide a supporting-frame A, adapted to be secured in position at the discharge end of a tile-forming machine, of which machine A' is the discharge-spout. Two upright crank-arms A² are pivotally secured in the bearings A³ at each end of the supporting-frame A and carry at their upper ends the swinging frame A⁴.

Two tile-receiving beds B and B' are mounted upon the swinging frame A⁴ and are connected with the side bars of said frame by means of the hinges B⁵. These tile-receiving beds each comprise a series of idler-rollers B⁶, over the rollers of each of which series runs an endless apron B⁷, of felt, canvas, or other suitable material. By reason of the crank-arm mounting of the swinging frame A⁴ said frame is movable from side to side to bring either one of the tile-receiving beds into alignment with the discharge-spout A' of the forming-machine. By reason of the hinge connection of said beds with the swinging frame A⁴ each bed is susceptible of being tilted into a vertical position to deliver the tile thereon to a pallet for transportation to the dry-room. At each of the outer corners of the tile-receiving beds B and B' is located an upwardly-extending handle B⁸, by means

of which the frame A⁴ is swung from side to side to place first one and then the other of the beds B and B' into coincidence with the discharge-spout of the tile-forming machine. These handles B⁸ are also employed to tilt the tile-receiving beds B and B' into a vertical position. The outer edge of each of the tile-receiving beds is provided with two arms C, pivotally connected with the side of said bed, so as to swing upwardly therefrom into a position substantially at a right angle with the plane of the bed. These arms are adapted to support a pallet C', (shown in dotted lines in Fig. 4,) upon which pallet the tiles are taken when the receiving-bed is swung into a vertical position for transportation from the machine to the dry-kiln.

A cutting-frame D, pivotally mounted in the supports D' upon the swinging frame A⁴ midway between the two tile-receiving beds B and B', is provided with the usual cutting-wires D² and is adapted to be swung sideways in either direction to cut into suitable lengths the long section of tile lying upon either receiving-bed. A standard D³ extends upwardly from the swinging frame A⁴ at one end of the cutting-frame D and carries at its upper end the vertically-movable holding-fork D⁴, supported yieldingly by means of the coil-spring D⁵. A stud D⁶, projecting from the side of the cutting-frame D, is adapted to engage the hollow of said fork to frictionally and releasably hold the cutting-frame in a vertical position.

To lock the swinging frame A⁴ in either of its two positions, I provide a latch E, mounted upon the arm E', supported in bearings E² upon the supporting-frame A, the rear extension of said latch carrying a sliding counterweight E³. The outer ends of said arm E' extend downwardly and thence forwardly through the standing loops E⁴, fixed in the supporting-frame A, and receive at their extremities a connecting foot-lever E⁵. The forward end of the latch E is adapted to engage an opening E⁶ in the under face of the swinging frame A⁴, one of which openings is located at each side of its longitudinal center. When it is desirable to swing said frame from one side to the other of the supporting-frame A, the operator depresses the foot-lever E⁵, withdrawing the latch E from

its opening E^6 , whereupon the frame is free to be swung to the opposite side of the supporting-frame, and when it is again in proper position the latch is released to the action of 5 the counterweight E^3 to enter the other opening E^6 .

A receiving-table F , having idler-rollers F' and an endless apron F^2 , the upper surface of said rollers and apron being in a plane 10 with those of the tile-receiving beds B and B' , is rigidly mounted upon the supporting-frame A at the discharge-spout A' of the forming-machine.

As hereinbefore stated, this cutting and 15 delivery apparatus is secured at the discharge end of a tile-forming machine with the receiving-table F coincident with the discharge-spout of said machine and in such position that the formed tile emerging from 20 said discharge-spout will be received upon said table F . The tile rests upon the endless apron F^2 , which, like the aprons B^4 , is formed of felt, canvas, or other suitable material. Outward movement of the tile moves the endless 25 apron F^2 , and one of the tile-receiving beds B and B' —for example, the bed B —having been placed in coincidence with the receiving-table F the tile continues in its forward movement, traversing the entire length of 30 the receiving-bed B . When the end of the tile reaches the outer end of the receiving-bed, the operator severs the length of tile that has emerged from the machine at or near the dotted line $a a$, Fig. 2, by any suitable hand 35 instrument. The locking-latch E is then depressed by the operator and the swinging frame A^4 moved to the opposite side of the supporting-frame, bringing the other tile-receiving bed B' into coincidence with the receiving-table F and in position to receive and 40 support the continuously-moving tile as it emerges from the discharge-spout A' . The section of formed tile sufficient in length to form two tiles of the usual size lying upon 45 the receiving-bed B' is now cut at its ends and near its middle by swinging down the cutting-frame D and passing the cutting-wires D^2 through the formed tile. By the arrangement of these cutting-wires each length 50 of tile is cut with a protecting-ring at each of its ends. A pallet C' is next placed by the side of each of the short lengths of tile and their protecting-rings and the hinged arms C of the bed B swung upward upon their pivotal 55 bearings. The tile-receiving bed B is then tilted into a vertical position, moving upon its hinges B^2 , which movement of the bed transfers each of the short lengths of tile, with its protecting-rings, from the endless 60 apron B^4 to one of the pallets C' , said pallet resting upon the hinged arms C . The pallets C' may now be removed, each with its length 65 of tile, to the dry-room.

It is clear that the beds B and B' might be 65 made without the rollers B^3 , that the endless aprons B^4 might be omitted, and that many other changes might be made in the embodied-

ment herein shown of my invention without departing from the spirit and scope thereof. Wherefore I desire to have it understood that 70 I do not limit myself to the specific construction herein set forth.

I claim as my invention—

1. In a delivery-table for tile-forming machines, in combination, a stationary supporting-frame; a swinging frame; means pivotally mounted on the supporting-frame for supporting the swinging frame; and two tile-receiving beds supported by said swinging frame. 75

2. In a delivery-table for tile-forming machines, in combination, a supporting-frame; a plurality of crank-arms pivotally mounted upon said frame; and a swinging frame supported by said crank-arms. 80

3. In a delivery-table for tile-forming machines, in combination, a supporting-frame; two tile-receiving beds adapted to be moved one at a time into coincidence with the discharge-spout of the tile-forming machine; and 85 means on the supporting-frame for holding said beds in position relative to said spout.

4. In a delivery-table for tile-forming machines, in combination, a supporting-frame; a swinging frame on said supporting-frame; two tile-receiving beds mounted on said swinging frame; and means on the supporting-frame for locking said swinging frame with relation to the supporting-frame. 90

5. In a delivery-table for tile-forming machines, in combination, a supporting-frame; a plurality of crank-arms pivotally mounted on said supporting-frame; a swinging frame carried by said crank-arms; two tile-receiving beds mounted on said swinging frame; and means for locking the swinging frame with relation to the supporting-frame. 95

6. In a cutting and delivery apparatus for tile-forming machines, in combination, means for moving a section of tile to one side of the discharge-spout of a tile-forming machine; and means for cutting such tile after withdrawal into suitable lengths. 100

7. In a cutting and delivery apparatus for tile-forming machines, in combination, a tile-receiving bed adapted to be placed in coincidence with the discharge-spout of a tile-forming machine; means for withdrawing said bed with a tile thereupon from coincidence with the discharge-spout; and means 105 for cutting a tile lying upon said withdrawn bed into suitable lengths. 110

8. In a cutting and delivery apparatus for tile-forming machines, in combination, two tile-receiving beds adapted to be placed one 115 at a time in coincidence with the discharge-spout of a tile-forming machine; means for withdrawing one of said beds with a tile lying thereupon from coincidence with the discharge-spout and for substituting the other 120 bed; and means for cutting a tile lying upon said withdrawn bed. 130

9. In a delivery-table for tile-forming machines, in combination, a supporting-frame;

a swinging frame; two tile-receiving beds mounted on said swinging frame; and a locking-latch mounted on said supporting-frame and adapted to engage with said swinging frame to lock said swinging frame with relation to said supporting-frame.

10. In a delivery-table for tile-forming machines, in combination, a supporting-frame; a swinging frame; two tile-receiving beds mounted on said swinging frame; a hinge connection between the swinging frame and each of said tile-receiving beds; and a pivoted arm on the outer side of each of said tile-receiving beds, which arm is adapted to hold a pallet.

11. In a cutting and delivery table for tile-forming machines, in combination, a supporting-frame; a plurality of crank-arms pivotally mounted in said supporting-frame; a swinging frame supported upon said crank-arms; two tile-receiving beds mounted upon said swinging frame; a hinge connection between each of said tile-receiving beds and said swinging frame; a locking-latch for holding the swinging frame from movement with relation to the supporting-frame; and an apparatus for cutting tile upon said tile-receiving beds into suitable lengths.

12. In a delivery-table for tile-forming machines, in combination, a supporting-frame; a swinging frame; two tile-receiving beds mounted upon said swinging frame; a latch for locking said swinging frame from movement with relation to said supporting-frame; and a foot-lever for releasing said locking-latch.

13. In a cutting and delivery table for tile-forming machines, in combination, a supporting-frame; a plurality of crank-arms pivotally mounted upon said supporting-frame; a swinging frame supported upon said crank-arms; two tile-receiving beds mounted upon said swinging frame; a hinge connection between each of said tile-receiving beds and said swinging frame; a receiving-table fixed with relation to the supporting-frame; a device adapted to cut tile upon the receiving-beds into suitable lengths; and a locking device

for holding the swinging frame from movement with relation to the supporting-frame. 50

14. In a cutting and delivery table for tile-forming machines, in combination, a supporting-frame; a swinging frame; two tile-receiving beds having a hinge connection with said swinging frame; and a cutting-frame pivotally mounted on said swinging frame.

15. In a cutting and delivery table for tile-forming machines, in combination, a swinging frame; two tile-receiving beds each adapted to be tilted into a vertical position; a cutting-frame pivotally mounted on said swinging frame; and means for holding said cutting-frame in an inoperative position.

16. In a cutting and delivery table for tile-forming machines, in combination, a swinging frame; two tile-receiving beds having a hinge connection with said swinging frame, each of said beds being provided with a series of idler-rollers and an endless apron adapted to run upon said rollers; and a cutting-frame pivotally mounted on said swinging frame.

17. In a delivery-table for tile-forming machines, in combination, a supporting-frame; a swinging frame; two tile-receiving beds mounted on said swinging frame, each of said beds being provided with a series of idler-rollers and an endless apron adapted to run upon said rollers; and means for locking said swinging frame with relation to the supporting-frame. 75

18. In a cutting and delivery table for tile-forming machines, in combination, a supporting-frame; a swinging frame; two tile-receiving beds mounted on said swinging frame, each of said beds being provided with a series of idler-rollers and an endless apron adapted to run upon said rollers; a cutting-frame pivotally mounted on said swinging frame; and means for holding said cutting-frame in an inoperative position. 85 90
